LAWN SPRINKLER

Herbert S. Ingham, Roslyn Estates, and Charles K. Wilson, East Williston, N. Y., assignors to Metallizing Engineering Co., Inc., Long Island City, N. Y., a corporation of New Jersey

Application September 25, 1951, Serial No. 16,742

Term of patent 14 years

(Cl. D91—1)

To all whom it may concern:

Be it known that we, Herbert S. Ingham and Charles K. Wilson, citizens of the United States, respectively, residing at 55 Serpentine Avenue, Roslyn Estates, county of Nassau, State of New York, and 204 Howard Street, East Williston, Long Island, State of New York, have invented a new, original, and ornamental Design for a Lawn Sprinkler, of which the following is a specification, reference being had to the accompanying drawing, forming a part thereof.

Fig. 1 is a top rear perspective view of a lawn sprinkler showing our new design.

Fig. 2 is a bottom front perspective view of the base portion of the lawn sprinkler shown in Fig. 1.

The dominant features of our design reside in those portions shown in full lines on the drawing.

We claim:

The ornamental design for a lawn sprinkler, as shown and described.

HERBERT S. INGHAM.
CHARLES K. WILSON.
